CIGAR WRAPPING MACHINE

Joseph W. Giles and William J. Giles, Philadelphia, Pa., assignors, by mesne assignments, to Jersey Cigar Machines, Inc., Belleville, N. J., a corporation of New Jersey

Application January 13, 1938, Serial No. 184,874

6 Claims. (Cl. 131—33)

The object of this invention is to devise a novel cigar wrapping machine which will operate faster than machines now in use, which will eliminate operations heretofore deemed essential and which will materially reduce the number of parts heretofore employed with a consequent reduction in the cost of manufacture.

A further object of the invention is to devise a cigar wrapping machine which will duplicate hand operation.

A further object of the invention is to eliminate all leaf carriers and the operation of transferring the leaf from the cutting die to leaf carriers, and also stretching devices.

15 A further object of the invention is to provide a definite speed relation between the rack and gear movement and the linear travel of the rolls over the wrapper.

20 A further object is to provide the crank with a cam capable of moving the rack rearwardly to increase the tension if more tension is desired on the wrapper.

25 A further object is to devise novel means to hold down the die plate while the knife rolls are cutting the wrapper. The holding means provide clearance for the rollers while moving over the die. The die plate raises when the wrapping machine is in position for tucking needle operation. This allows the cigar to rest on the die plate and prevents wrinkling of the wrapper.

30 A further object is to have the cutting arms operated by the movement of the carriage, thus eliminating cams and their timing.

35 A further object is to have a crank arm motion which controls practically all movements of the machine.

40 A further object is to devise novel means to control a tension plate to hold the wrapper in exact position relatively to the head of the cigar.

45 With the above and other objects in view as will hereinafter clearly appear, our invention comprehends a novel cigar wrapping machine.

Other novel features of construction and advantage will hereinafter more clearly appear in the detailed description and the appended claims.

50 For the purpose of illustrating the invention, we have shown in the accompanying drawings a typical embodiment of it, which, in practice, will give reliable and satisfactory results. It is, however, to be understood that this embodiment is typical only and that the various instrumentalities of which our invention consists can be variously arranged and organized, and the invention 55 is not limited to the precise arrangement and

organization of these instrumentalities as herein set forth.

Figure 1 is a top plan view of a cigar wrapping machine embodying our invention.

Figure 2 is a side elevation with certain parts 5 broken away.

Figure 3 is a perspective view of header mechanism and its adjuncts.

Figure 4 is a perspective view of the die, bunch carrying rolls and associated mechanism. 10

Figure 5 is an end elevation with a shaft in section showing rack driving mechanism and the needle mounting.

Figure 6 is a perspective view of needle operating mechanism. 15

Figure 7 is an end elevation showing more particularly the driving means for the bunch carrying rollers.

Figure 8 is a side elevation of a portion of the bunch carrying mechanism. 20

Figure 9 is a section on line 9—9 of Figure 8.

Figure 10 is an end view of a portion of Figure 8.

Figure 11 is a sectional elevation of the die and its adjuncts. 25

Figure 12 is a section on line 12—12 of Figure 11.

Figure 13 is a side elevation of knife controlling mechanism.

Figure 14 is a side elevation of stop mechanism 30 for controlling the header roller.

Figure 15 is a perspective view of lever mechanism seen in Figure 14.

Figure 16 is an end elevation.

Figure 17 is a detail of the carriage and rolls. 35

Figure 18 is a side elevation of a portion of the machine.

Similar numerals indicate corresponding parts.

Referring to the drawings:

1 designates the frame of the machine, the 40 construction and arrangement of which can vary widely in practice.

The machine is driven by a motor 2 having its shaft provided with a pulley 3 around which passes a belt 4 which latter also passes around 45 a pulley 5 on a crank shaft 6 suitably journaled in the machine frame.

The crank shaft has a disc 33 with a wrist pin 7, on which is loosely mounted one end of a link 8, the opposite end of which is mounted on a 50 stud 9 carried by a lever 10 fixed to a rock shaft 11 on the main frame. The upper end of the lever 10 has a stud 12 connected by a link 13 with a stud 14 secured to a bracket 15 fixed to a reciprocating carrier 16 of the rolling mechanism, 55

This carrier 16 has rollers 17 which roll on bars 18. Attached to the carrier 16 is a carriage 19 in which is journaled a shaft 20. A pawl plate 21, see Figs. 8 and 10, is fixed to one end of the shaft 20, and carries a spring pressed pawl 22, which cooperates with a ratchet 23 to be driven thereby. The ratchet 23 is secured to a gear 24, loosely mounted on the shaft 20. The gear 24 receives its motion through a rack 25 as the carriage moves over the rack, see Figs. 1, 2, and 5 and, independently, by a cam movement consisting of a stud 26 on the rack, a link 27 connected with the stud 26 and a stud 28, the latter being connected with a cam lever 29 fulcrumed at 30 on the frame and having a roller 31 which rides on a cam 32 on the crank disc 33 to which the wrist pin 7 is secured, see Figs. 1 and 2. The rack 25 is free to slide in the ends of the main frame.

20 A gear 34 is fixed to the shaft 29, see Figure 8, and drives a gear 35 on a fluted roller shaft 36 journaled on the carriage 19. The shaft 36 has fixed to it a gear 37 which drives gears 38, see Figure 7. The gears 38 have fixed to them gears 39, and both gears are free to rotate on their shafts 40, and free to rock in the carriage 19. Also mounted on the shafts 40 are rock arms 41 and 42, see Figure 4, in which fluted rolls 43 are free to revolve, and on the ends of the rolls, gears 44 are mounted which are driven by gears 39.

The fluted rollers support the bunch and rotate it.

The bunches are fed from the bottom between the fluted rolls, either manually or mechanically in any conventional manner.

25 The rock arms 40, are tensioned, by springs 45, against adjustable stops 46, secured to brackets 47, on roller frame 19.

The tucking needle

40 48 is the tucking needle, see Figure 6, secured to a rod 49 which is free to rotate and to move longitudinally in a bearing 50 on the carriage 19. The rod 49, at the end opposite the needle, has spaced collars 51 fixed to the rod. The free end of a drying member 52 extends between the collars and is connected to a lever 53, fulcrumed on the carriage 19. A lever 54 pivoted at 55 to the carriage 19 has the rod 49 passing through it, and raises and lowers such rod and the tucking needle. The lever 54 has an arm 56 fixed to it and the lower end of such arm is in the path of a cam 57. The downward movement of the lever 54 is limited by an adjustable stop 58. The cam 57 is formed on a lever 59 fulcrumed on the machine frame at 60, see Figure 1. The lever 59 is connected by a link 61 with a lever 62 fulcrumed at 30, and provided with a roller 63 which cooperates with a cam 64 on the crank disc 33.

60 The lever 53 has a roller 65, which cooperates with a cam 66 on the lever 59 to move the needle rearwardly.

The forward movement of the needle is caused by a stud 67 on the lever 53 contacting with the cam 66.

65 The shaft 20 has fixed to it a ratchet 68, see Fig. 4, cooperating with a pawl 69 to prevent rearward rotation of the fluted rolls. The carriage 19 has bars 70 and 71, the latter being fixed at its lower end to a rod 72, mounted in a rock bracket 73, carrying a plate 74, tensioned by a spring 75. The head end of the leaf adheres, due to the paste applied to it, to the bottom of the plate 74 after being transferred from the cutting plate to cause a tension on the wrapper, so that

the head end of the cigar can be smoothly wrapped. The carriage 19 has a stationary knife 76, see Figures 3 and 4, on which is pivoted at 77 a movable knife 78. The movable knife is in the form of a lever having an arm 79, connected by a link 80 with a lever 81, fulcrumed at 82 on a bar 83, secured to the support 19. A spring 84 actuates the movable knife. The lever 79 has a trip stop 85 which cooperates with a stop 86, fulcrumed at 87 to hold the movable knife open.

10 The upper end of the lever 81 contacts with a roller 88, see Figs. 1 and 13, to open the movable knife. The roller 88 is mounted on a stationary bracket 89 fixed to the main frame.

15 A bracket 90, fixed to the bracket 89, forms a fulcrum for a lever 91, held by a spring 92 against a stop 93.

Secured to the carriage 19, is a header block 94, see Figure 3, shaped to suit the end of the cigar. 95 is a cone shaped roll free to revolve 20 on a stud 96, on a lever 97, pivoted at 98. The other end of the lever 97 is slotted at 99 to receive a stud 100, secured to a lever 101, fulcrumed on a shaft 102, on a bracket 103, on the bracket 83, see Figure 3. The shaft 102 has a lever 104, 25 having fixed to it a stop 105, which is pressed against a lever 106 by a spring 107. The lever 106 is fulcrumed on a stud 108 secured to the carriage 19. An arm 109 extending from the lever 106 travels in the path of a lever 110, see Figs. 30 14 and 15, moving the lever 106 away from the stop 105. The lever 110 is pivoted on a stud 111 on the support 19. The upper end of the lever 110 has secured to it a spring 112, of sufficient strength to trip the lever 106.

35 The other end of the spring 112 is secured to a lever 113, mounted on the stud 111, and having a stop stud 114 to retain the lever 110 against the action of the spring. A spring 115 holds the lever 113 against a stop 116, carried by the bracket 89.

117 are wrapper cutting rolls, mounted on shafts 118, carried by a lever 119, on a rock shaft 120, on the main frame 1. A lever 121 is secured to the upper end of the rock shaft 120, and has 45 a roller 123 secured to the roller frame 16.

The die mechanism

124 is a cutting die, see Fig. 11, secured to a die box 125 fixed to the machine frame and having suction holes 126 at its top. Inside of the die and free to move upwardly and downwardly, is a suction plate 127 having suction holes 128. The suction plate is fastened to a rod 129, which is guided in a bearing sleeve 130 on the box 125. 55 The rod 129 has a slot 131, into which a lever 132 extends to hold the die plate downwardly. The lever 132 is in the form of a plate and is fulcrumed at 133 on the die box 125. The lower end of rod 129 has a pin and slot connection at 134 with a lever 135, fulcrumed at 136 on the main frame. A cam 137, mounted on lever 135, cooperates with a roller 138 mounted on a lever 139, which is secured to the rock shaft 11. A spring 140 secured to the lever 135 tends to raise the die 60 plate 127.

65 A lever 141 fulcrumed at 142 on the main frame, see Figure 1, has, at its free end, a stud 143, which bears against the lever 132 to move it out of the slot 131 of rod 129, such action being caused by one end of the lever 141 engaging a fixed stop 144 on the roller frame 16.

70 The die plate has a slot 145 into which the tucking needle is adapted to pass.

75 The operation of the machine will now be

readily apparent to those skilled in this art and is as follows:

All of the operations of the machine are controlled by a common crank shaft which has a 5 crank controlling a reciprocatory rack, the speed of which can be varied to vary the speed of rotation of the bunch to provide a greater stretch in the wrapper.

The bunch to be wrapped is inserted in any 10 desired manner, for example by hand, between the fluted bunch carrying rolls 36 and 43. A leaf of tobacco is stretched by hand over the die plate 127 and die block 125, being retained thereon by suction through the holes 126 and 128. 15 The machine starts and rollers 117 carried by arm 119 are moved over the die. When the roller 122, see Figure 1, moves forwardly in the cam track 123, the rollers travel over the die 124 and die plate 127 causing the leaf of tobacco to be 20 cut to the contour of the die plate, thus forming the wrapper. When the rollers are returning the operator strips the excess leaf off of the die block 125, and applies paste to the head end of the wrapper. During this operation the die plate 25 127 is in its downward position, being held by pawl 132 in slot 131, see Figure 11.

During the time the rollers are cutting the leaf, the carriage 19 has moved forwardly to the 30 position at which the cigar is to be inserted. As the carriage 19 passes over the die plate 127, its motion stops at the point where the tucking needle 48 is in alignment with slot 145 in the die plate 127. At this time, there is a dwell in the movement as the crank is going over dead center. 35 As the carriage is moving back the pawl lever 54 rides on the cam 57, see Figure 6, causing the forward end of the tucking needle to move downwardly to be in alignment with the slot 145, so that it can pass beneath the wrapper. At this 40 time the pin 144, see Fig. 1, contacts with lever 141 causing pin 143 to push lever 132 out of the slot 131, allowing the die plate to move upward due to spring 140.

The tucking needle is moved into the slot by 45 the roller 63 engaging cam 64, see Fig. 2, and moving cam lever 62, link 61, and lever 59 on its pivot. The stop lug 66 is engaged by the rod 67 on the lever 53, see Fig. 6. This causes the link 50 52 to move the tucking needle forwardly into the slot 145 beneath the wrapper. As the tucking needle moves in, the arm 56 passes over the cam 57, and the lever 54 moves downwardly, raising the tucking needle against the bunch. Now the 55 carriage starts forwardly to roll the wrapper around the bunch.

During this forward motion, the speed of the fluted rolls 36 and 43 may be varied to rotate the bunch faster than it is passing over the die 60 plate to obtain a desired stretch in the leaf. This motion is produced by moving the rack in the opposite direction to the movement of the carriage, through link 27, lever 29 and roller 31 riding on cams 32 secured to crank disc 33. 65 Movement is imparted to the fluted rolls 36 and 43 from the rack by the gear 24, see Figures 5 and 8.

The tucking needle being pressed against the 70 cigar rotates with the bunch in its journal 50. After the end of the leaf is tucked in, or about one and one half revolutions, the needle is withdrawn. As the roller 63 rides over its cam 64, the lever 59 is returned to its normal position, bringing the stop lug 66 against the roller 65,

which turns lever 53 to withdraw the tucking needle.

As the carriage moves forwardly to the head end of the cigar, the tension plate 14 moves over the head end of the wrapper, and the die plate 127 moves downwardly allowing the wrapper to adhere to the tension plate 14. The die plate is moved downwardly by cam 137 contacting with roller 138 on moving arm 139, at which time, the plate 132 enters slot 134 holding down the die 10 plate. The downward movement of plate 14 is limited by a stop 146, see Figure 4. At the proper time, just before the flag of the wrapper is wrapped around the bunch, a portion of the flag is adhering to the vertical portion of the tension 15 plate 14. At this time, the movable knife 78, which is in its open position, now operates and nicks the wrapper. At this time the cone shaped header roll 95 moves in against the bunch, causing the wrapper to be wrapped conically around 20 the head of the bunch. The movable knife is pivoted at 77 on the stationary knife 76. The lever 79 is a part of the movable knife and is operated through link 80, lever 81 and spring 84 25 to hold the movable knife closed.

As the carriage 19 moves forwardly to the end of its stroke, the free end of the lever 81 contacts with the stationary roller 88 opening the movable knife; at which time the lever 86 pivoted at 87 moves over a notch in the plate 85, holding the 30 knife in open position. A spring 147, see Figure 3, holds the lever 86 in holding position. The knife is permitted to operate during the forward movement of the carriage by the free end of the lever 86 contacting the lever 91 disengaging the 35 lever 86 from the notch in the lever 85. The lever 91 is held by the spring 92 against the stop 93. On the return of the carriage, the movable knife remains open due to the spring mounting 40 of lever 91.

The header roll 95, on lever 97 is moved by the arm 109 contacting the lever 110, see Figures 14 and 15.

The arm 110 is prevented from moving by the 45 spring 112, which is of sufficient strength for this purpose. The lever 110 is retained in position against the stop 114 on the lever 113. The lever 113 is held in position against the stop 116 by the spring 115. As the stop 109 is moved, the lever 106 moves away from the pin 105, allowing the lever 104 through the spring 106 to move. The lever 104 is fast on shaft 102 and rocks lever 101, and, through pin 100, see Figure 3, in slot 99 moves lever 97 inwardly.

The cigar is removed from its carrying rolls by moving the bell crank levers which support the lower fluted roller.

Having thus described our invention, what we claim as new and desire to secure by Letters Patent is:

1. In a cigar wrapping machine, a wrapper cutting die, a carriage, means on the carriage for rotating in one direction a bunch to be wrapped, means to prevent the bunch from rotating in the opposite direction when the carriage moves towards the die to prevent the wrapper from unwrapping, and means to reciprocate the carriage.

2. In a cigar wrapping machine, a frame, rack 65 slidable in the frame, a cutting die, a reciprocatory carriage, rolls mounted on the carriage and revolved by the rack to roll a bunch over the die, and means to move the rack rearwardly to increase the tension on the wrapper.

3. In a cigar wrapping machine, a cutting die,

- rolling mechanism movable over the die, a carriage on which the rolling mechanism is mounted, a rack operating said rollers and controlling the stretch of a leaf on the die, a tucking needle, and
5 a crank mechanism for moving the carriage and comprising a crank disc connected by a linkage with the carriage, said crank disc having two cams one of which controls the rack and the other of which controls the tucking needle.
- 10 4. In a cigar wrapping machine, a stationary cutting die with a die plate having a groove in its top face, a carriage, rolling mechanism on the carriage and movable over the die, means to raise the die plate, comprising a rod connected with the plate, and a resiliently urged lever connected with said rod, cam means to lower the plate, locking and releasing means for said rod, a tucking needle, and a crank mechanism controlling said carriage and causing said tucking
15 needle to enter said groove when the die plate is raised and the crank is at dead center.
- 20 5. In a cigar wrapping machine, a die, a car-

riage, rollers mounted on the carriage and movable over the die, a tension plate resting on the wrapper and pressing it against the die to prevent it from slipping during the rolling operation, means to reciprocate said carriage, and means to control said tension plate.

6. In a cigar wrapping machine, a wrapper cutting die having a die plate to be raised and lowered relatively thereto, a carriage movable over the die, a rod connected with the die plate and having a slot, a fulcrumed lever having a pin and slot connection with said rod, a spring acting on said lever and tending to raise said die plate, a cam on said lever, a rock arm having a roller to engage said cam to cause the lowering of said die plate, a locking lever to enter the slot of said rod to hold down the die plate, a lever having a stud bearing against said locking lever to move it out of its slot, and means to actuate said last named lever.

JOSEPH W. GILES.
WILLIAM J. GILES.
